US00D661251S

(12) **United States Design Patent**
Cheng et al.

(10) **Patent No.:** US D661,251 S
(45) **Date of Patent:** ** Jun. 5, 2012

(54) **BATTERY CONNECTOR**

(75) Inventors: **Hsiung-Kuei Cheng**, Taipei (TW);
Huang-Chih Chen, Taipei (TW)

(73) Assignee: **Cyber Power System Inc.**, Taipei (TW)

(**) Term: **14 Years**

(21) Appl. No.: **29/355,501**

(22) Filed: **Feb. 9, 2010**

(51) **LOC (9) Cl.** **13-02**

(52) **U.S. Cl.** **D13/120**

(58) **Field of Classification Search** D13/118-121,
